UNITED STATES PATENT OFFICE.

ROBERT J. HARRY, OF HATTIESBURG, MISSISSIPPI.

HORIZONTAL RATCHET FEED FINGER FOR SAW GRINDERS.

Application filed May 25, 1928. Serial No. 289,451.

The present invention relates to a horizontal ratchet feed finger for operation upon practically all types of automatic saw grinders and is desired for carrying the saw teeth under the emery with an even motion without any danger of injuring the teeth by dulling the sharpened edges thereof.

Another very important feature of the invention resides in the provision of a structure of this nature which releases around the teeth rather than over the ends thereof as is the common practice.

A still further very important object of the invention resides in the provision of a horizontal feed finger of this nature which is exceedingly simple in its construction, strong and durable, and thoroughly efficient and reliable in use and operation.

With the above and numerous other objects in view, the invention resides in certain novel features of construction, and in the combination and arrangement of parts as will be hereinafter more fully described and claimed.

In the drawing:

Figure 1 is a side elevation of a device embodying the features of my invention showing the same with portions of the conventional saw grinder,

Figure 2 is a top plan view thereof,

Figure 3 is a bottom plan view thereof,

Figure 4 is a longitudinal section therethrough,

Figure 5 is a transverse section therethrough taken substantially on the line 5—5 of Figure 4,

Figure 6 is another bottom plan view thereof, showing the parts adjusted to a different position to that shown in Figure 3,

Figure 7 is a perspective view of the arm of the device,

Figure 8 is a rear elevation of the device, and

Figure 9 is a perspective view of the engaging key.

Referring to the drawing in detail it will be seen that the numeral 5 denotes a knuckle including a body with one end thickened and provided with an opening 6 extending from side to side and having a bushing 7 therein to form a bearing for receiving the wrist pin 8 of a suitable rocker 9.

Conventional adjusting means 10 is associated with the head of the rocker to control the wrist pin 8. The other end of the

knuckle 5 is extended downwardly and provided with a notch 11. Adjacent this other end a knuckle is provided with an opening 12 for loosely receiving a vertical stud bolt 13 which is anchored as will be hereinafter claimed.

A pair of stud bolts 14 are threaded through the knuckle between the openings 6 and 12 and adjacent the latter and may be locked in adjusted position by means of jam nuts 15. A U-shaped plate 16 is disposed over the intermediate portion of the knuckle 5 and the bolts 13 and 14 extend through openings therein.

A yoke 17 comprises a substantially rectangular body with an opening 18 adjacent one end and a pair of longitudinally spaced openings 19 intermediate its ends and an opening 20 adjacent its other end for threadedly receiving the stud bolt 13 and from said other end there extends a tongue 21 into the notch 11.

The ends of the plate 16 terminate to the sides of this yoke to prevent lateral play of the knuckles and the yoke in relation to each other. A spring 22 is disposed about the bolt 13 impinging against the head 13' thereof at its upper end and against the plate 16 to urge the knuckle downwardly toward the yoke, it being noted that the stud bolts 14 engage or bear against the yoke 17 to space the bearing end portion of the knuckle from the yoke the desired distance against the action of the spring 22.

The numeral 24 denotes an elongated arm provided intermediate its ends with a longitudinally spaced opening 25 to receive bolts 26 which extends through the opening 18 to rockably mount the arm on the yoke so that said arm may swing in a horizontal plane.

A transverse slot 27 is formed in the arm 24 at one end under the yoke 17 and receives the bolt 28 which is engaged in one of the openings 19. Thus it will be seen that the arm may be adjusted in respect to the yoke by changing bolts 26 and 28 in respect to the respective openings 25 and 19, the two positions being illustrated in Figures 3 and 6.

A tongue 30 projects from the end of the arm 24 under the yoke 17 adjacent one side edge thereof and from the opposite side edge of the yoke 17 there depends a stud 31. The tongue and stud are provided with pins 32 projecting toward each other.

The ends of a coil spring 33 are disposed about the stems 32 and impinge against the

stud 31 and the tongue 30 to normally hold the arm longitudinally aligned with the yoke, it being seen that the arm may be rocked to the limit afforded by the pin and slot connection provided by bolt 28 and slot 27.

Under the free end of the arm 24 there is mounted a longitudinally extending shoe 34 adjustably mounted by means of bolts 35 extending through transverse slots 36 formed 10 in the arm 24. This shoe is adapted to engage against a stop pin 37 or the like provided on the platform 38 of the automatic grinder.

A key 39 of trapezoidal cross sectional 15 formation is slidable in a transverse channel 40 provided on the upper face of the free end of the arm 24 being of dove tailed formation. One end of this key 39 is beveled inwardly toward the pivoted end of the 20 arm.

From the above detailed description it will be seen that as the rocker 9 swings in the direction of the arrow 43 in Figure 1 the grinder 44, of course, is out of engagement 25 with the saw 45 and the key 39 is engaged with its beveled end 41 between two of the teeth of the saw 45 thereby causing the saw to advance and then as the rocker moves in an opposite direction to arrow 43 the beveled 30 end 41 will cause the arm 24 to swing in the direction of the arrow 46 in Figure 2 so as to pass around the tooth of the saw rather than over the tooth of the saw and in this 35 way the movement of the key will in no way dull the tooth which has just been sharpened.

The connection between the knuckle and the yoke afforded by the bolt 13 with its 40 spring 22 compensates for the arcuate movement of the head of the rocker 9 and tends to more firmly hold the key in engagement with the saw as it is advancing the saw as will be apparent.

This tension, of course may be adjusted 45 by the stud bolts 14. With this device it is possible to obtain an even stroke at all times without any danger of injuring, dulling or otherwise detrimentally affecting the saw teeth. The structure is simple, capable of all 50 necessary adjustments, may be manufactured at a low cost and yet be strong and durable, and thoroughly efficient and reliable in use and operation.

It is thought that the construction, operation, utility and advantages of the invention 55 will now be quite apparent to those skilled in this art without a more detailed description thereof.

The present embodiment of the invention 60 has been disclosed in detail merely by way of example, since in actual practice it attains the features of advantage enumerated as desirable in the statement of the invention and 65 the above description.

It will be apparent that changes in the details of construction, and in the combination and arrangement of parts may be resorted to without departing from the spirit or scope of the invention as hereinafter 70 claimed or sacrificing any of its advantages.

Having thus described my invention, what I claim as new is:

1. A feed finger for saw grinders comprising a rocker arm knuckle including a body 75 having a bearing at one end for engagement with the rocker arm, an opening adjacent the other end and a notch at said other end, a yoke having a tongue at one end in the notch; and an arm, means pivoting an intermediate portion of the arm below the other end of the yoke, a pin and slot connection between the yoke and the arm to limit the swinging of the arm in relation to the yoke, a key extending laterally from the arm, a 80 bolt extending through the opening in the knuckle and engaged with the yoke, a spring on the bolt impinging against the knuckle, and a bolt threaded through the knuckle to bear against the yoke. 85

2. A feed finger for saw grinders comprising a rocker arm knuckle including a body having a bearing at one end, an opening adjacent the other end and a notch at 90 said other end, a yoke having a tongue at one end in the notch, an arm, means pivoting an intermediate portion of the arm below the other end of the yoke, a pin and slot connection between the yoke and the arm to limit the swinging of the arm in relation to the yoke, a key extending laterally from the arm, a bolt extending through the opening in the 95 knuckle and engaged with the yoke, a spring on the bolt impinging against the knuckle, a bolt threaded through the knuckle to bear against the yoke, and a U-shaped plate on the knuckle extending 100 down to terminate alongside of the yoke to limit lateral movement of the yoke and the knuckle in relation to each other. 105

3. A feed finger for saw grinders comprising a rocker arm knuckle including a body having a bearing at one end with which the wrist pin of a rocker may engage, an opening adjacent the other end and a notch at said other end, said other end with the notch being extended downwardly, a yoke having a tongue at one end in the notch, an arm, means pivoting an intermediate portion of the arm below the other end of the yoke, a pivot slot connection between the yoke and the arm to limit the swinging of the arm in relation to the yoke, a key extending laterally from the arm, a bolt extending through the opening in the 115 knuckle and engaged with the yoke, a spring on the bolt impinging against the knuckle, and a bolt threaded through the knuckle to bear against the yoke. 120

4. A feed finger for saw grinders comprising 130

- ing a rocker arm knuckle including a body having a bearing at one end with which the wrist pin of a rocker may engage, an opening adjacent the other end and a notch at 5 said other end, said other end with the notch being extended downwardly, a yoke having a tongue at one end in the notch, an arm, means pivoting an intermediate portion of the arm below the other end of the yoke, a 10 pivot slot connection between the yoke and the arm to limit the swinging of the arm in relation to the yoke, a key extending laterally from the arm, a bolt extending through the opening in the knuckle and engaged with the yoke, a spring on the bolt impinging against the knuckle, and a bolt threaded through the knuckle to bear against the yoke, a shoe 15 adjustably mounted on the free end of the arm to cooperate with a pin on the grinder to limit the movement of the arm toward the saw being operated upon in the grinder.
5. A feed finger for saw grinders comprising a rocker arm knuckle including a body having a bearing at one end for engagement with the rocker arm, an opening adjacent the other end and a notch at said other end, a yoke having a tongue at one end in the notch; and an arm, means pivoting an intermediate portion of the arm below the other end of the yoke, a pin and slot connection 20 between the yoke and the arm to limit the swinging of the arm in relation to the yoke, a key extending laterally from the arm, a bolt extending through the opening in the knuckle and engaged with the yoke, a spring on the bolt impinging against the knuckle, and a bolt threaded through the knuckle to bear against the yoke, a key extending laterally from the arm, a 25 bolt extending through the opening in the knuckle and engaged with the yoke, a spring on the bolt impinging against the knuckle, and a bolt threaded through the knuckle to bear against the yoke, a key extending laterally across the free end of the arm having a beveled end for engaging with the saw in the grinder.
6. A feed finger for saw grinders comprising a rocker arm knuckle including a body having a bearing at one end for engagement with the rocker arm, an opening adjacent the other end and a notch at said other end, a yoke having a tongue at one end in the notch; and an arm, means pivoting an intermediate portion of the arm below the other end of the yoke, a pin and slot connection 30 between the yoke and the arm to limit the swinging of the arm in relation to the yoke, a key extending laterally from the arm, a bolt extending through the opening in the knuckle and engaged with the yoke, a spring on the bolt impinging against the knuckle, and a bolt threaded through the knuckle to bear against the yoke, a key extending laterally across the free end of the arm having a beveled end for engaging with the saw in the grinder.

In testimony whereof I affix my signature.

ROBERT J. HARRY.
